UNITED STATES PATENT OFFICE.

HENRY F. HERBIG, OF MAPLEWOOD, NEW JERSEY, ASSIGNOR TO THE COMMERCIAL CABLE COMPANY, OF NEW YORK, N. Y., A CORPORATION OF NEW YORK.

METHOD OF AND APPARATUS FOR AMPLIFYING ELECTRIC SIGNAL IMPULSES.

Application filed August 26, 1925. Serial No. 52,574.

The invention relates particularly to a shadow may be oscillated on the two cells 55 method of and apparatus for amplifying in response to the oscillations of the string electric impulses transmitted as signals. conductor of the galvanometer.

The circuit and apparatus are especially 5 adapted for amplifying electric impulses transmitted over a submarine cable and also impulses transmitted over conductors in land line telegraphy.

The apparatus consists of a string gal- 10 vanometer, which is the signal-receiving instrument; an optical system combined with the string galvanometer, and photo-electric cells in circuit with one or more thermionic vacuum tube amplifiers.

15 The electrical signals transmitted are received by means of the string galvanometer, the string conductor of which is suspended in a very strong magnetic field and is energized to a state of motion by the received 20 electric impulses. The photo-electric cells are illuminated by light from a suitable light source, after it traverses a path in which is suspended the string conductor, a suitable optical system being provided for 25 this purpose. The illumination of the photo-electric cells is varied by the movement of the string conductor in the path of light, its shadow being projected on part of the light sensitive substance of the photo- 30 electric cells. This variation of the amount of light on the two cells causes a variation of potential of the grid filament circuit of a thermionic vacuum tube amplifier. This 35 variation of potential in the grid-filament circuit causes a variation in the plate circuit of the vacuum tube amplifier. A siphon recorder, relay or other suitable recording device, may be connected in the plate circuit of the vacuum tube amplifier to record or 40 retransmit the variations of the plate current.

The light source and the beam of light therefrom is stationary or fixed. The string conductor is vibrated in its magnetic field 45 and by its vibrations varies the position of its sharply defined shadow on the two photo-electric cells. There is no additional burden imposed on the string conductor and the sensitiveness of the galvanometer is not affected. The shadow of the string conductor 50 is preferably greatly magnified by the optical system in order that it may be cast on two photo-electric cells arranged side by side. By means of this arrangement the

In the drawings:

Fig. 1 is a perspective diagrammatic view 60 of a portion of an apparatus for carrying out the invention;

Fig. 2 a diagrammatic view of the two photo-electric cells; and

Fig. 3 a diagrammatic view of the elec- 65 trical apparatus showing the several cir- 70 cuits.

Referring to Fig. 1, 1 designates an in- 75 candescent lamp which is a source of light energy for the system. 2 designates an optical condenser system, for concentration of 80 the light. 3 designates an adjustable sub- stage optical condenser system for concentrat- 85 ing the light in a small point at the string conductor 4. The current at the receiving end of the cable flows through the conductor 4. (See Fig. 3.) 5 designates a strong magnet which may be either a permanent magnet or an electromagnet as de- 90 sired. The magnet may be of any form. It is shown as a horseshoe magnet with wide 95 gaps between the pole pieces merely for the sake of simplicity and clearness in the drawings. In practice the pole pieces would be much nearer to the string conductor 4 than is indicated in Fig. 1, and of a form to give a very strong magnetic field along the length 100 of the string conductor. The condenser 3 is adjustably mounted in one of the pole pieces axially in line with the condenser 2. In the other pole piece is an adjustable tubular support for housing the optical mi- 105 croscopic objective system 6, said support being axially in line with the condenser 3 and the condenser 2. The string conductor 4 is arranged between the pole pieces and passes through the axial line of the optical system. By means of the microscopic ob- 110 jective system a greatly enlarged sharp image, indicated by the cross lines 7, of the string conductor 4 is produced on the sur- 115 faces of the two photo-electric cells 8 and 9, said cells being properly arranged or placed side by side to receive said sharp shadow or image. Referring to Fig. 2, *b* and *b*¹ indicate the light sensitive electron emitting substances which are known as cathodes. *a* and *a*¹ designate the anodes.

In this view the cross lined area 7 indicates

- one position which the image or shadow of the string conductor 4 may have on the light sensitive substance b and b^1 . It is obvious that the shadow may be arranged in other 5 positions, but it is preferred to have the shadow cover approximately one-half of each cell. This is the position indicated in Fig. 2 and is also the position of the shadow indicated in Fig. 3.
- 10 Part of the light produced by the lamp 1 is focused by means of the optical condenser system 2 and the optical substage condenser system 3 on the string conductor 4. When the current of the cable at the receiving end flows through the string conductor 4 in the direction indicated by the arrow head c , the string conductor is deflected in the direction indicated by the arrow head d . This causes the shadow 7 of 15 the string conductor 4 to move in one direction, while when the current above referred to flows in the opposite direction to that indicated by the arrow head c , the string conductor 4 is deflected in the opposite direction 20 of that indicated by the arrow head d . In either case of the direction of current flow through the string conductor 4, the string conductor always moves perpendicular to the direction of the magnetic field produced by the magnet 5. By means of the microscopic objective system 6 a sharp image 25 of the string conductor 4 is projected on part of the light sensitive surface of each of the photo-electric cells 8 and 9. By referring to Fig. 2, one manner in which the image of the string conductor 4 is projected on the light sensitive substances b and b^1 , of the photo-electric cells, may be observed. The image 7 of the string conductor 4 is, 30 therefore, moved either to the right or left, depending upon the direction of current flow through the string conductor 4. Except for the dark image 7 of the string conductor 4, the light sensitive surfaces b and b^1 of the photo-electric cells 8 and 9 are 35 illuminated. The illumination mentioned is caused by the light that traverses the optical system but which is not interrupted by the string conductor 4.
- 40 The circuits connecting the photo-electric cells and the vacuum tube amplifier are clearly shown in Fig. 3 and the operation of the parts will be clearly understood by reference to that figure.
- 45 When there is no incoming signal the dark shadow 7 of the string conductor 4 is projected so that it lies partially on the light sensitive surfaces b and b^1 of the photo-electric cells 8 and 9 respectively; the remaining light sensitive surfaces of the cells 50 8 and 9 being illuminated by the light that is not interrupted by the string conductor 4. With this condition, there is a steady effective potential in the grid filament circuit of 55 the vacuum tube 17. The grid filament cir-

cuit is as follows: grid 19, through the parallel combination of: battery 15, anode a of photo-electric cell 8, cathode b of same cell, and cathode b^1 of photo-electric cell 9, anode a^1 of the same cell, battery 16; then 70 through the resistance 22 and to the cathode 18 of the vacuum tube 17. With this steady potential of the grid filament circuit, there is a steady flow of current in the plate circuit of the vacuum tube 17, caused by the 75 plate battery 23. Under this condition part of this plate current flows through the windings of the relays 27 and 28. It is desirable to have no current flowing through the relay windings when there is no signal being sent. 80 It is, therefore, necessary to have the potential at the upper end of the relay winding No. 27 equal to that at the lower end of relay winding No. 28. A biasing battery 24 and a variable resistance 25, which are in series, 85 are connected in shunt with the circuit including the mil-ammeter 26 and relays 27 and 28 in series. The potential and polarity of battery 24 is of such a value as to just compensate for the voltage drop across the 90 resistance 25. Or it may be stated otherwise, that the value of the resistance is such that the voltage drop across its terminals, caused by the current flowing through it, is equal in numerical value to that of the biasing 95 battery.

When a signal is received, there is an unbalance of the potential across the relay windings, due to the change of the grid potential of the vacuum tube, and current flows 100 in a clockwise or counter-clockwise direction through the relay windings, depending upon whether the potential of the grid is greater than or less than the normal value, the normal value referring to the condition when 105 the mil-ammeter indicates zero.

A mil-ammeter 26 is connected in the circuit as shown, to indicate when there is no current flowing through the relay windings; hence also indicating equal potentials at the 110 two extremes of the relay windings. It is convenient for the mil-ammeter 26 to have the zero mark in the center of its scale. Any unbalance can then be readily detected.

Current is received through the cable 12, 115 and part of this current flows through the string conductor 4, thence through the artificial line to ground. Assume that the direction of current flow is such as to cause the image 7 of the string conductor 4 to 120 move to the left, decreasing the illumination on the light sensitive substance b of the photo-electric cell 8, and increasing the light on the light sensitive surface b^1 of the photo-electric cell 9. The effective impedance of 125 the photo-electric cell 8 is greatly increased, while that of the photo-electric cell 9 is greatly decreased. This causes the potential of the grid 19 to become more positive 130 with respect to the filament 18. Grid 19

under this condition is also more positive than it was previously when there was no signal being received.

The grid 19 becoming more positive than it was originally when there was no signal being received, the internal impedance of the vacuum tube 17 is also correspondingly decreased. Therefore, the plate current is likewise increased, causing the relay or recorder to record or retransmit the signal impulse received.

When the signal is in the opposite direction from that assumed above, the shadow of the string conductor 4 moves to the right, thereby causing the light on the photo-electric cell 8 to increase, decreasing its impedance, while the light on the cell 9 is decreased, causing its impedance to increase. The potential of the grid 19 is then decreased in value with respect to the filament 18 below that which it had been when there was no signal being sent. The internal impedance of the filament plate circuit of the vacuum tube 17 is increased in value above that which it had when there was no signal, causing a corresponding decrease in the plate current. The recorder or relay then operates in an opposite manner to that of the case previously described and records or retransmits this signal which is also opposite to that of the first case. In this manner signals of either positive or negative polarity are amplified and recorded or retransmitted.

By giving the shadow of the string conductor sufficient area and sufficient movement one or the other of the photo-electric cells may be placed completely in shadow for each movement or signal. By total darkness, or excluding the light from one cell, the impedance of that cell is so increased that it is cut out of the circuit and the battery connected thereto is rendered ineffective. It is to be noted that battery 15 has its positive pole connected to the anode a of the cell 8; and that battery 16 has its positive pole connected to the anode a^1 of cell 9. With the cell 8 totally eclipsed the battery 15 is rendered ineffective in the circuit and the battery 16 therefore effectively increases the positive potential of the grid 19. With the cell 9 in total eclipse the battery 16 is rendered ineffective in the circuit and the battery 15 then positively and materially increases the negative potential of the grid 19. By providing the two sources of electric current, that is to say the two batteries 15 and 16, and arranging them in the circuit as shown in Fig. 3, very positive and material changes in the potential of the grid may be obtained, to the extent of rendering one of said batteries totally ineffective and allowing the other battery to have its full effect upon the grid.

What I claim is:

1. An apparatus for receiving and amplifying electric signal impulses comprising a galvanometer having an element adapted to be vibrated by the incoming signal impulses and having a normal zero position, means for concentrating light rays upon said element whereby said element will cast a shadow and move said shadow as the element vibrates, means for amplifying or enlarging said shadow, a pair of photo-electric cells in the path of said enlarged shadow whereby a portion of each of said cells will be covered by said shadow in the normal position of the said element, a three-element vacuum tube having its grid-filament circuit connected to the two photo-electric cells, and means in the plate circuit of said vacuum tube to reproduce amplified signal impulses corresponding to the impulses received by the galvanometer.

2. An apparatus for receiving and amplifying electric signal impulses comprising a galvanometer having an element adapted to be vibrated by the incoming signal impulses and having a normal zero position, means for concentrating light rays upon said element whereby said element will cast a shadow and move said shadow as the element vibrates, means for amplifying or enlarging said shadow, a photo-electric cell in the path of said enlarged shadow whereby a portion of said cell will be covered by said shadow in the normal position of the said element, a three-element tube having its grid-filament circuit connected to the said photo-electric cell, and means in the plate circuit of said vacuum tube to reproduce amplified signal impulses corresponding to the impulses received by the galvanometer.

3. An apparatus for receiving and amplifying electric signal impulses comprising a string galvanometer having a string conductor adapted to be vibrated in two directions by the incoming signal impulses and having a normal zero position, means for concentrating light rays upon said string conductor whereby said conductor will cast a shadow, means for amplifying or enlarging said shadow, a pair of photo-electric cells in the path of said enlarged shadow whereby a portion of each of said cells will be covered by said shadow in the normal position of the string conductor, a three-element vacuum tube, a battery having its positive pole connected to the anode of one photo-electric cell its negative pole being connected to the cathode of the other photo-electric cell and to the grid of the vacuum tube, a battery having its positive pole connected to the anode of one photo-electric cell and its negative pole connected to the cathode of the other photo-electric cell and to the filament of the said vacuum tube, whereby the positive pole of one of said batteries will be connected to the anode of

- one photo-electric cell, and the positive pole of the other of said batteries will be connected to the anode of the other photo-electric cell, and means adapted to be operated by the amplified impulses in the plate circuit of the said vacuum tube, said impulses corresponding to the impulses received by the galvanometer.
4. An apparatus for receiving and amplifying electric signal impulses, comprising a string galvanometer having a string conductor adapted to be vibrated in two directions by the incoming signal impulses and having a normal zero position, means for concentrating light rays upon said string conductor whereby said conductor will cast a shadow, means for amplifying or enlarging said shadow, a pair of photo-electric cells in the path of said enlarged shadow whereby a portion of each of said cells will be covered by said shadow in the normal position of the string conductor, a three-element vacuum tube, a battery connected to each photo-electric cell, the positive pole of one of said batteries being connected to the anode of one photo-electric cell and the positive pole of the other of said batteries being connected to the anode of the other photo-electric cell, and means adapted to be operated by the amplified impulses in the plate circuit of the said vacuum tube, said impulses corresponding to the impulses received by the galvanometer.
5. The method of receiving and amplifying electric impulses, consisting in producing a constant normal flow of electrons in a light sensitive electron discharge device by partially illuminating said device from a fixed source of light and partially darkening said device by a sharply defined shadow of a vibratory impulse-receiving element, causing a variation in said electron flow by moving the shadow to cover more or less of said device as the impulse receiving element is vibrated by the received impulses, and then utilizing the variations in the said electron flow to control means to reproduce and amplify impulses corresponding to the impulses received.
6. An apparatus for receiving and amplifying electric signal impulses comprising a string galvanometer having a string conductor adapted to be vibrated in two directions by the incoming signal impulses from a normal zero position, means for concentrating light rays upon said string conductor whereby said conductor will cast a shadow and move said shadow as the conductor vibrates, means for amplifying or enlarging said shadow, a pair of photo-electric cells in the path of said enlarged shadow whereby a portion of each of said cells will be covered by said shadow in the normal position of the string conductor, a thermionic vacuum tube amplifier having its grid-filament
7. An apparatus for receiving and amplifying electric signal impulses comprising a string galvanometer having a string conductor adapted to be vibrated by the incoming signal impulses and having a normal zero position, means for concentrating light rays upon said string conductor whereby said conductor will cast a shadow and move said shadow as the conductor vibrates, means for amplifying or enlarging said shadow, a photo-electric cell in the path of said enlarged shadow whereby a portion of said cell will be covered by said shadow in the normal position of the string conductor, a thermionic vacuum tube amplifier having its grid-filament circuit connected to the said photo-electric cell, and means in the plate circuit of said vacuum tube to reproduce amplified signal impulses corresponding to the impulses received by the string conductor.
8. An apparatus for receiving and amplifying electric signal impulses comprising a string galvanometer having a string conductor adapted to be vibrated by the incoming signal impulses and having a normal zero position, means for concentrating light rays upon said string conductor whereby said conductor will cast a shadow and move said shadow as the conductor vibrates, means for amplifying or enlarging said shadow, a photo-electric cell in the path of said enlarged shadow of the string conductor, a thermionic vacuum tube amplifier having its grid-filament circuit connected to the said photo-electric cell, and means in the plate circuit of said vacuum tube to reproduce amplified signal impulses corresponding to the impulses received by the string conductor.
9. An apparatus for receiving and amplifying electric signal impulses, comprising a galvanometer having an element in a normal zero position and adapted to be vibrated by incoming signal impulses; means for concentrating light rays upon said element whereby said element will cast a shadow and vary said shadow as the element vibrates; a photo-electric cell in the path of said shadow, whereby a portion of said cell will be covered by said shadow in the normal position of the said element and more or less of said cell will be affected by said shadow as the element vibrates; a three-element tube having its grid-filament circuit connected to the said photo-electric cell; and means in the plate circuit of said vacuum tube to reproduce amplified signal impulses corresponding to the impulses received by the galvanometer.
10. An apparatus for receiving and am-

- plifying electric signal impulses, comprising a galvanometer having an element in a normal zero position and adapted to be vibrated by incoming signal impulses; means for 5 concentrating light rays upon said element whereby said element will cast a shadow and vary said shadow as the element vibrates; a pair of photo-electric cells in the path of said shadow, whereby a portion of 10 each of said cells will be covered by said shadow in the normal position of the said element and more or less of said cells will be affected by said shadow as the element vibrates; a three-element vacuum tube having 15 its grid-filament circuit connected to the said two photo-electric cells; and means in the plate circuit of said vacuum tube to reproduce amplified signal impulses corresponding to the impulses received by the galvanometer.
- 20 11. An apparatus for receiving and amplifying electric signal impulses, comprising a galvanometer having an element in a normal zero position and adapted to be vibrated in one direction by an incoming signal impulse of positive current and to be vibrated 25 in the opposite direction by an incoming signal impulse of negative current; means for concentrating light rays upon said element whereby said element will cast a shadow and move said shadow as the element vibrates; means for amplifying or enlarging 30 said shadow; a photo-electric cell in the path of said enlarged shadow whereby a portion of said cell will be covered by said shadow 35 in the normal position of the said element; a three-element tube having its grid-filament circuit connected to the said photo-electric cell; and means in the plate circuit of said vacuum tube to reproduce amplified signal 40 impulses corresponding to the impulses received by the galvanometer.
12. An apparatus for receiving and amplifying electric signal impulses, comprising a galvanometer having an element in a normal zero position and adapted to be vibrated 45 in one direction by an incoming signal impulse of positive current and to be vibrated in the opposite direction by an incoming signal impulse of negative current; means 50 for concentrating light rays upon said element whereby said element will cast a shadow and move said shadow as the element vibrates; means for amplifying or enlarging 55 said shadow; a pair of photo-electric cells in the path of said enlarged shadow whereby a portion of each of said cells will be covered by said shadow in the normal position 60 of the said element; a three-element vacuum tube having its grid-filament circuit connected to the said two photo-electric cells; and means in the plate circuit of said vacuum tube to reproduce amplified signal impulses corresponding to the impulses received by the galvanometer.
- 65 13. The method of receiving, amplifying and reproducing electric signal impulses, consisting in producing a sharply defined shadow of the vibrating element of a sensitive receiving instrument adapted to be vibrated in two directions from normal or zero 70 position by positive and negative current impulses; arranging the vibrating element of the receiving instrument to vibrate freely and thereby retain its sensitiveness unrestricted and unimpaired; causing said vibrating element to cast a shadow and move said shadow as the vibrating element is moved; causing said shadow in its normal or zero position to partially darken a light-sensitive cell to thereby produce a constant 75 normal flow of electric current through said cell, the current flow being varied as the shadow is caused to affect more or less of the said cell through the vibrations of the vibrating element of the receiving instrument; 80 and then utilizing the variations of the said current flow to control means to reproduce and amplify impulses corresponding in character and duration to the impulses which caused the movement of the vibrating element of the receiving instrument.
14. The method of receiving, amplifying and reproducing electric signal impulses, consisting in producing a sharply defined shadow of the vibrating element of a sensitive receiving instrument adapted to be vibrated from normal or zero position by received current impulses; arranging the vibrating element of the receiving instrument 85 to vibrate freely and thereby retain its sensitiveness unrestricted and unimpaired causing said vibrating element to cast a shadow and move said shadow as the vibrating element is moved; causing said shadow in its normal or zero position to partially darken 90 a light-sensitive cell to thereby produce a constant normal flow of electrons in said cell, the electron flow being varied as the shadow is caused to affect more or less of the said cell through the vibrations of the vibrating element of the receiving instrument; and then utilizing the variations of the said electron flow to control means to reproduce and amplify impulses corresponding 95 in character and duration to the impulses which caused the movement of the vibrating element of the receiving instrument.
15. The method of receiving, reproducing and amplifying electric signal impulses, consisting in receiving said signal impulses on a signal-receiving device having a freely vibrating element in a normal zero position and adapted to be freely vibrated by current impulses without transmitting mechanical or electrical energy to any other apparatus, 100 whereby said element will retain its sensitiveness unrestricted and unimpaired and will not be retarded in its movements; and associating the said vibrating element of the receiving instrument with an amplifying and 105
- 110 115 120 125 130

- reproducing means to affect said amplifying and reproducing means by light rays to reproduce the received signal impulses without mechanical or electrical connection between the vibrating element of the receiving apparatus and the amplifying and reproducing apparatus.
16. The method of receiving, reproducing and amplifying electric signal impulses, consisting in receiving said signal impulses on a signal-receiving device having a freely vibrating element in a normal zero position and adapted to be freely vibrated by current impulses, and thereby retain its sensitiveness unimpaired, whereby said element will not be retarded in its movements; and associating the said vibrating element of the receiving instrument with an optical system and with an amplifying and reproducing means to affect said amplifying and reproducing means by light rays to reproduce the received signal impulses, whereby the amplifying and reproducing means will be operated without mechanical or electrical connection between the vibrating element of the

receiving apparatus and the amplifying and reproducing apparatus.

17. The method of receiving, reproducing and amplifying electric signal impulses of positive, negative and zero current character, consisting in receiving said signal impulses on a sensitive signal-receiving device having a vibrating element in a normal zero position and adapted to be vibrated in one direction by positive current impulses and to be vibrated in the opposite direction by negative current impulses; and arranging said vibrating element of the receiving instrument to vibrate freely in an optical system to affect an amplifying and reproducing means by light rays without reducing the sensitiveness of the vibrating element and without mechanical or electrical connection between the vibrating element of the receiving apparatus and the amplifying and reproducing apparatus.

In testimony whereof I hereunto affix my signature.

HENRY F. HERBIG.
